UNITED STATES PATENT OFFICE.

EDWARD A. FARR, OF MERIDEN, CONNECTICUT, ASSIGNOR TO MANNING, BOWMAN & COMPANY, OF MERIDEN, CONNECTICUT, A CORPORATION OF CONNECTICUT.

DESIGN FOR A DISH.

42,200.

Specification for Design.

Patented Feb. 27, 1912.

Application filed August 24, 1911. Serial No. 645,850. Term of patent 7 years.

To all whom it may concern:

Be it known that I, EDWARD A. FARR, a citizen of the United States, residing at Meriden, county of New Haven, State of Connecticut, have invented a new, original, and ornamental Design for a Dish, of which the following is a specification, reference being had to the accompanying drawings, forming a part thereof, in which—

Figure 1 is a side elevation of a dish show-

ing my new design; Fig. 2 is a plan view thereof.

I claim:

The ornamental design for a dish, as shown.

EDWARD A. FARR.
